his Attorney.

UNITED STATES PATENT OFFICE.

WINSLOW W. DUNN, JR., OF ST. PAUL, MINNESOTA.

TAG HOLDER.

Application filed December 23, 1921. Serial No. 524,470.

To all whom it may concern:

Be it known that I, WINSLOW W. DUNN, Jr., a citizen of the United States, residing at St. Paul, in the county of Ramsey and State of Minnesota, have invented a new and useful Improvement in Tag Holders, of which the following is a specification.

My invention relates to tag holders and has for its object to provide a device adapted to be used in an exposed position which will prevent rain or water from running down through the top of the device and along the tag and thereby obliterating the matter contained on said tag.

Another object is to provide means for permitting of inserting the tag from the window of the same and for permitting said tag to be removed directly outwardly from said window.

A still further object is to provide means whereby the said holder can be readily attached to a hooped keg or tub.

In carrying out my objects I provide a rectangular frame having a window or opening through the same, which frame is formed on three sides with rabbeted recesses. In conjunction with this I provide my tags of a height just sufficient to pass between the opening of said window and arrange the upper portion of said frame in the form of a water table to shed off rain or water which may run down along the side of the tub or keg and prevent the same from flowing directly over the card and obliterating the matter contained thereon.

The full objects and advantages of my invention will appear in connection with the detailed description thereof and are particularly pointed out in the claims.

In the drawings, illustrating the application of my invention in one form:—

Fig. 1 is a perspective view of a tub showing my applied invention thereto with one of the tags partly removed therefrom.

Fig. 2 is a front elevational view of a portion of the tub shown in Figure 1 drawn to a larger scale indicating the position of the tag when the same is correctly placed therein.

Fig. 3 is a rear view of the holder shown in Figure 2 detached from the tub.

Fig. 4 is a view similar to Figure 2 showing the method of inserting the tag into the holder.

Fig. 5 is a sectional view taken on line 5—5 of Fig. 4.

Fig. 6 is a view similar to Figure 5 showing the position of the tag within the holder just prior to the same dropping into place.

Fig. 7 is a section on line 7—7 of Figure 2 and drawn to a larger scale showing the method of applying the finger to the tag to remove the same from the holder.

In Figure 1 I have shown an ordinary tub 10 to which my invention may be attached. This tub may be made of a wooden stave construction held together by a number of hoops 11, 12, and 13. This tub may be of any suitable construction and is merely illustrated to show the application of my invention thereto. My invention as best shown in Figure 2 comprises a holder indicated in its entirety at A, which comprises two uprights 14 and 15 connected at the top and bottom by an upper member 16 and lower member 17. The inner portions of the uprights 14 and 15 are rabbeted inwardly at 18 and 19 leaving marginal strips 20 and 21 extending upwardly along the outer portion thereof. The exact shape of the front of uprights 14 and 15 does not affect the invention though the said members are preferably formed with slanting sides. Upper member 16 and lower member 17 are formed curved to fit upon the exterior surface of the tub 10 on which the device is applied. Lower member 17 is formed with a rabbeted recess 22 leaving a marginal strip 23, which recess connects with the recesses 18 and 19 in uprights 14 and 15 forming a three sided frame with these uprights and said lower member.

For holding the holder A in place upon the tub 10 I form the same with four ears 24, 25, 26, and 27, extending outwardly adjacent the four corners thereof, which ears are drilled and counter-sunk to receive four wood screws 28 adapted to be screwed into the body portion of the tub 10. The two

marginal strips 20 and 21 of uprights 15 and 14 are cut away to form recesses 29 and 30 to allow the device to be placed over the upper hoop 11 of the tub, which hoop when 5 the device is securely screwed to the tub lies within the recesses 29 and 20. It will be noted from Figures 3 and 5 that the inner surface 31 of the upper member 16 and the inner surface of the marginal strips 20 and 21 10 and 23 are so formed as to lie flush against the surface of the body portion of the tub 10 when the holder A is tightly screwed to the said tub.

The shape of the tag used with this holder 15 can best be seen in Figures 4 and 5. In these figures a tag 32 is shown having the necessary information indicated at 33 thereon. This tag is of a height slightly less than the distance between the upper and lower 20 members 16 and 17 of the holder A, and of a width just equal to the circumferential distance around the tub 10 between the extreme corners of the rabbeted recesses 18 and 19. In mounting the tag in the holder 25 the tag is grasped by one hand and placed between the upper and lower frame members 16 and 17 and one edge of the same is slid inwardly within one of the rabbeted recesses 18 or 19 as the case may be. The tag then occupies a position shown in Figures 4 and 5 with the other edge protruding outwardly beyond one or the other of the uprights of said holder. The next step 30 in inserting the tag into the holder consists of catching the protruding end of the tag with the extreme end of the finger and buckling the tag towards the inserted end as shown in Figure 6. After this position has been taken a slight pressure inwardly 35 of the tag disengages the same from the other upright and the second edge of said tag slides inwardly into the other of the recesses 18 and 19. This leaves the tag with its right and left edges positioned within 40 the appropriate recesses and the remainder of the tag positioned midway between the two upper and lower members 16 and 17. By catching the extreme upper corner of the tag 32 with the finger nail as clearly 45 shown in Figure 7 the entire tag may be slid downwardly until the lowermost edge thereof rests in the recess 22 as clearly brought out in this figure. It can be noted that the depth of the recesses 18, 19 and 50 22 is slightly greater than the combined width of the hoops 11 and the tag 32 so that the said tag slides easily into place without interfering with said hoop.

For shedding the water which may spill 60 over the top of tub 10 and directly down the sides, and for shedding any rain which may drain along the side of said keg away from the tag 33 I form upper member 16 in the shape of a water table which as before 65 stated has its face lying snug up

against the body portion of the tub 10. The exact construction of this member is best shown in Figure 7 where it will be noted that the outer surfaces 34 and 35 of this device slope downwardly so as to eliminate the formation of any pocket in which to catch the water and so as to shed the water outwardly from the tag proper. It will be further noted that the surface of member 16 indicated at 36 slopes inwardly 70 towards the tub 10. In like manner member 17 is formed with an outwardly sloping surface 37 and a sloping rear surface 38 which serve to direct the water away 75 from the tag thereby preserving the said tag and the written matter thereon.

In removing the tag from the holder the finger is inserted as shown in Figure 7 with the nail engaging the upper portion of the tag. By drawing the central part of the upper portion of the tag by means thereof outwardly as shown in Figure 1 the entire tag is quickly pulled out of the holder.

It can readily be seen with my invention 90 that a tag may be easily inserted into the holder or removed therefrom, that when in place the upper member or water table serves to shed any water which may come from the spilling of the contents of the tub 10 over the edge thereof or from any other 95 source away from the tag positioned within the holder so that the same is kept clean and legible.

In accordance with the patent statutes I 100 have described the principles of operation of my invention together with the apparatus which I now consider to represent the best embodiment thereof, but I desire to 105 have it understood that the construction shown is only illustrative and that the invention can be carried out by other means and applied to uses other than those above set forth within the scope of the following claims.

I claim:—

1. A tag holder including a horizontal upper member adapted to form a water shed, an under surface formed on said horizontal member adapted to extend flush with the front opening of said tag holder, side and bottom members connected with said horizontal member and a marginal recess formed on the inner side of said side and bottom members adapted to receive a tag.

2. A tag holder comprising upper and lower horizontal members, a pair of uprights connecting said horizontal members, rabbeted recesses formed along the backs of the lower horizontal and side members, a downwardly inclined surface formed on said upper horizontal member and a downwardly inclined surface formed on said lower horizontal member commencing at the recess within the same.

3. A card holder including members

joined together to form a rectangular frame, a marginal engaging recess formed in the back face of three of the sides of said frame, and a smooth slightly inwardly beveled under surface formed along the edge of the other of said members to form a water shed and closure for the upper side of said

holder which is adapted to lie closely against the holder support and to prevent the upper edge of the card from entering 10 below said upper member.

In testimony whereof I affix my signature.

WINSLOW W. DUNN, JR.
